UNITED STATES PATENT OFFICE.

SAMUEL MILNE, OF EDINBURGH, SCOTLAND.

APPARATUS FOR WASHING OR SIMILARLY TREATING PULP.

1,267,683.

Specification of Letters Patent.

Patented May 28, 1918.

Application filed December 26, 1916. Serial No. 138,985.

To all whom it may concern:

Be it known that I, SAMUEL MILNE, a subject of the King of Great Britain and Ireland, and resident of Edinburgh, Scotland, have invented certain new and useful Improvements in Apparatus for Washing or Similarly Treating Pulp, of which the following is a specification.

This invention relates to the washing of pulp and refers more particularly to the washing of pulp made from waste papers to insure the removal of printing ink and the like. It may also be used for washing pulp after digestion or after bleaching, and it is particularly suitable for cleaning fibers which contain gritty or sedimentary matter. Printed papers, such as old newspapers and the like, are usually first reduced to pulp by any of the well known methods, such as by kneaders, potchers, beaters, refiners, or the like, in the presence of an alkali or other suitable compound which will combine with the oil in the ink. The pulping is carried out until the fibers are thoroughly separated and the particles of carbon loosened from them, so that they may be easily washed away without loss of fiber. Hitherto, the ink, loading, or other deleterious matter has been removed by the ordinary drum washers or concentrators, which work on the surface of the pulp, or by passing the pulp on an endless wire cloth under sprinklers or spray pipes, the sprays passing through the pulp and forcing the impurities through the wire cloth, or by treating the pulp in a rotating wire-covered drum with spray pipes inside to force the impurities through.

In the course of my experiments I have found that when the pulp is spread on a wire cloth, the impurities readily settle down, and as they are of a muddy character, they clog the meshes of the wire cloth, so that strong sprays of water, if applied above the pulp, are necessary to keep the wire cloth clean. These strong sprays cause a great loss of fiber, a considerable proportion of the fiber being carried through the wire cloth by the force of the sprays.

I have found, however, that when the sprays are directed to the underside of the wire cloth the meshes are easily kept clear and the impurities readily pass through with much less loss of fiber than by any other method, and this application of the sprays to the opposite side of the wire cloth, to keep the wire cloth clean and to lift the

pulp slightly from it, forms the basis of this invention.

Several embodiments of the invention are illustrated on the accompanying drawings 60 in which:

Figure 1 is a side elevation of the preferred form of the invention in which the wire cloth receives a reciprocating horizontal movement. Fig. 2 is a part sectional plan 65 view of Fig. 1. Fig. 3 is an end elevation, and Figs. 4 and 5 are detail views of the cloth tray supports. Fig. 6 is an enlarged detail view showing the action of the spray.

The invention will now be described with 70 reference to Figs. 1 to 5 of the accompanying drawings, in which wire cloth *a* is secured to a frame *b*, which has sides *c* to confine the pulp and constituting a bed or tray for the same. The frame *b* is provided 75 with trunnions *d* at each corner to receive trunnion bearings in the form of sleeves *e*, which are formed with spherical bulbous parts *f* adapted to engage correspondingly shaped parts in the connecting rods *g* and 80 be rigidly secured thereto by the bolts *h*. Grooves are provided in the trunnions to accommodate studs *h'* in the sleeves *e* to keep the parts in engagement. The lower ends of the rods *g* are similarly connected 85 to floor brackets *i*, so that when assembled, the tray is capable of reciprocation in the longitudinal direction.

Below the frame *b* is a second frame *j*, which is supported on the members *k* having cross-bars *l* for the purpose. The ends of said cross-bars enter sleeve bearings *m* on the frame *j*, while a second set of cross-bars *n* are provided on the frames *k*, the ends of which are adapted to engage further 95 sleeve bearings *o* secured to the brackets *i*, the arrangement being such that this frame also is capable of reciprocation in the longitudinal direction. Carried on the frame *j* are a series of pipes *p* lying transversely of 100 the tray *a*, said pipes being connected, by the flexible connections *q*, with the main supply pipe *r*, valves *s* being interposed to control the supply to each pipe. The latter are perforated on the top side so that the 105 water can gush forth in a series of jets on to the underside of the cloth tray *a*.

At one end of the tray *a*, housings are provided to receive two crank shafts *t* and *u*. The crank *t* is coupled by the connecting 110 rod *v* to the tray *a* and is rotated by a belt and pulley from a suitable source of power

w. The crank *u* is rotated by means of gearing from the same source of power, but at a different rate of speed and said crank is coupled by the connecting rods *x* to the frame *j*.

In operation, the pulp is led on to the tray *a* and the water turned on to the sprinklers *p*. The cranks *t*, *u* are then rotated, causing the pulp and sprinkler frames to reciprocate, the tray *a* moving quickly so as to cause the pulp to gradually move along said tray while the frame *j* moves at a considerably lower rate of speed. By these means the water impinges on the underside of the wire cloth, on which the impurities from the pulp settle, and washes said impurities away whereby the meshes are easily kept clear.

The bracket *i* is provided with means to raise or lower the lower ends of the connecting rods so that the frames carrying the wire cloth may be raised or lowered at that end to regulate the thickness of the pulp being treated, the washed pulp being discharged into a box, spout or chest as may be convenient.

I wish it to be understood that the invention is not confined precisely to the embodiments shown for carrying it into effect, as the details of construction may be varied without departing from the spirit of the invention.

What I claim is:—

1. Apparatus for treating pulp comprising, in combination, a pulp tray of wire cloth, a frame to support said tray, means to support said frame, a second frame mounted below the pulp tray, a series of sprinklers mounted on said second frame, a fluid conduit, connections between said conduit and the sprinklers, means to reciprocate the pulp tray and means to alter the inclination of said frames to the horizontal plane, substantially as described.

2. Apparatus for treating pulp comprising, in combination, a pulp tray of wire cloth, a frame to support said tray, connecting rods to support said frame, a second frame mounted on rocking members below the pulp tray, a series of sprinklers mounted on said second frame, a fluid conduit, connections between said conduits and the sprinklers, means to reciprocate the pulp tray and means to reciprocate the sprinklers relatively to said pulp tray, substantially as described.

3. Apparatus for treating pulp, comprising, in combination, a cloth tray, a frame with sides to support said tray, a second frame below the tray, a series of sprinklers on said second frame, a water conduit, flexible connections between the conduit and the sprinklers, valves to control the flow of the fluid, rocking members to support the frames, cranks and connecting rods to reciprocate said frames together with gearing to actuate said frames at different relative speeds, substantially as described.

4. Apparatus for treating pulp, comprising, in combination, a cloth tray, a frame with sides to support said tray a second frame below the tray, a series of sprinklers on said second frame, a water conduit, flexible connections between the conduit and the sprinklers, valves to control the flow of the fluid, rocking members to support the frames, cranks and connecting rods to reciprocate said frames together with means to vary the inclination of the first mentioned frame and the sprinkler frame to the horizontal plane, substantially as described.

In witness whereof I have hereunto set my hand in the presence of two witnesses.

SAMUEL MILNE.
